UNITED STATES PATENT OFFICE.

E. G. F. ARNDT AND AUGUSTUS HÜHNE, OF RONDOUT, NEW YORK.

IMPROVEMENT IN LOCKS.

Specification forming part of Letters Patent No. 36,886, dated November 11, 1862.

To all whom it may concern:

Be it known that we, E. G. F. ARNDT and AUGUSTUS HÜHNE, of Rondout, in the county of Ulster and State of New York, have invented certain new and useful Improvements on Door-Locks; and we do hereby declare the following to be a full, clear, and exact description thereof, reference being had to the accompanying drawings, and to the letters and marks thereon.

The improvements herein recited relate to a lock wherein with only one bolt the lock may be used as a right or left hand lock, as a latch-lock, as a night-lock, or a day-lock, the bolt being moved either with or without the key. The case and the different parts of the lock may be made of any metal commonly used in making locks, either by being cast or wrought, or certain parts cast and the other wrought, as is usual in manufacturing locks for doors.

The drawings forming part of this specification represent a door-lock having our improvements, Figure 1 thereof being a front elevation of the lock and catch, the bolt being thrown out as used for a latch-lock; Fig. 2 being a like view of the lock with the bolt thrown out to its fullest extent, as when locked, and the button for removing the bolt having been removed; Fig. 3 being a like view of the lock with the bolt out to its fullest extent, and there held by the guard-plate against the button of the bolt; Fig. 4 being an under side view of the bolt with its tumblers detached from the case; Fig. 5 being a view of the interior of the lock with the bolt out as a latch-bolt, the inner plate of the lock having been removed, and Fig. 6 being a like view of the lock without the inner plate, the bolt being thrown fully out or locked.

In each of these figures, where like parts are shown, like letters and marks are used to indicate the parts.

The case of the lock *a* with the catch or hasp *b* and the end of the bolt *c* are so constructed that the lock may be used as a right or left hand lock or latch-lock. The bolt has a coiled or helical spring, *d*, the tendency of which is to throw it out, secured by a pin, *e*, to the case of the lock and by a like pin to the bolt. The bolt also has a pair of tumblers, *f f*, vibrating or susceptible of being

moved on pins *g g*, affixed to the bolt. One of the tumblers has a spring, *h*, which tends to force the tumblers toward each other, and both have studs or projections *i*. In one of the tumblers is a hole, *j*, for the button *k*.

Through the case of the lock, at a proper point, is a hole for the play of the hub *l* of the spindle of the door-knobs. The hub *l*, as is shown, has the usual spindle-pole, *m*, and also has a coiled or helical spring, *n*, attached to it by a pin at a central point, *o*, the spring being also attached by a pin, *p*, to the case of the lock.

When this lock is used as a latch or catch lock, the studs *i i* of the tumblers rest against the back portion or side of the stud *q q* of the hub *l*, and the bolt is moved backward by the usual turning of the knob's spindle, the forward movement of the bolt being produced by the action of the spring *d*. The tendency of the spring *n* is to keep the hub *l* in such position that its studs *q q* will be in a vertical line—*i. e.*, a line at right angles to that of the bolt *c*. This use of the lock is shown more particularly by Fig. 5.

When used as a day-lock, the bits of the key are brought in contact with the projection *r* of the one tumbler, forcing apart the tumblers, and as the key is further turned, the bits coming in contact with the projection *s* of the bolt, the bolt is moved forward to the full locking extent, as is indicated by Fig. 6. When fully locked, as is shown by Fig. 6, the studs *i i* of the tumblers are in front of the studs *q q* of the hub, and consequently the thrust of the bolt under any effort to force it inward will be resisted by the hub.

As a day-lock or as a night-lock, the bolt may be moved by the key from the outer side of the door, and also by any person within the house on the inner side of the door by a stud or button, *k*, which is attached to the tumbler, as before stated, at *j*. The bolt may, however, be held secure when in the locked position, so that it cannot be moved by the key by the guard-plate *t*, which, as is shown by Fig. 3, will prevent the button from being moved, and consequently hold firmly the bolt.

A curved slot, *u*, in the case allows the necessary motions of the button for moving the bolt or for moving with it when operated upon it by the key.

What we claim as our invention, and desire to secure by Letters Patent, is—

1. The arrangement of the tumblers *f f* in their relation to the bolt and to the hub so that the hub shall bear the thrust of the bolt when pressure is made at the outer end of it, as set forth.
2. The spring *n*, as it is attached to and operates upon the hub, as described.
3. The guard-plate *t*, in combination with

the button *k* and tumblers *f f*, as herein recited.

This specification signed this 11th day of August, 1862.

E. G. F. ARNDT.
AUG. HÜHNE.
